US00D999826S

(12) **United States Design Patent** (10) **Patent No.:** **US D999,826 S**
Waldman (45) **Date of Patent:** **** Sep. 26, 2023**

(54) **LABEL FOR PACKAGING FOR DOSAGE FORM**

(71) Applicant: **Johnson & Johnson Consumer Inc.**, Skillman, NJ (US)

(72) Inventor: **Joel H. Waldman**, Chalfont, PA (US)

(73) Assignee: **Johnson & Johnson Consumer Inc.**, Skillman, NJ (US)

(**) Term: **15 Years**

(21) Appl. No.: **29/762,602**

(22) Filed: **Dec. 17, 2020**

(51) LOC (14) Cl. **19-08**

(52) U.S. Cl.

USPC **D20/23**; D20/27; D9/434

Primary Examiner — Catherine Ho

(57) **CLAIM**

The ornamental design for a label for packaging for dosage form, as shown and described.

DESCRIPTION

FIG. 1 is a perspective view of a first embodiment of a label for packaging for dosage form;

FIG. 2 is a perspective view of a second embodiment of a label for packaging for dosage form;

FIG. 3 is a perspective view of a third embodiment of a label for packaging for dosage form;

FIG. 4 is a perspective view of a fourth embodiment of a label for packaging for dosage form;

FIG. 5 is a perspective view of a fifth embodiment of a label for packaging for dosage form; and,

FIG. 6 is a perspective view of a sixth embodiment of a label for packaging for dosage form.

The broken lines are included for the purpose of illustrating unclaimed portions of the label for packaging for dosage form and form no part of the claimed design.

1 Claim, 6 Drawing Sheets
